(57) **CLAIM**

The ornamental design for a hose pot as shown and described.

DESCRIPTION

FIG. 1 is a top front left perspective view of the hose pot of the present invention;

FIG. 2 is a bottom front right view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top front right side view thereof; and,

FIG. 10 is a bottom front left view thereof.

The portions of the hose pot illustrated in broken lines form no part of the claimed design.

1 Claim, 10 Drawing Sheets
